US00D902206S

(12) **United States Design Patent** (10) **Patent No.:** **US D902,206 S**
Laurans et al. (45) **Date of Patent:** **** Nov. 17, 2020**

(54) **KEY PAD**(71) Applicant: **SimpliSafe, Inc.**, Boston, MA (US)(72) Inventors: **Charles Laurans**, Brookline, MA (US);
Yong Zhao, Medford, MA (US);
Melina Engel, Belmont, MA (US);
Rahul Subramany, Boston, MA (US);
Gregory Wolos, Somerville, MA (US)(73) Assignee: **SimpliSafe, Inc.**, Boston, MA (US)(**) Term: **15 Years**(21) Appl. No.: **29/676,972**(22) Filed: **Jan. 16, 2019**(51) **LOC (12) Cl.** ..... **14-02**(52) **U.S. Cl.**USPC ..... **D14/383**; D8/331(58) **Field of Classification Search**USPC D14/383, 385, 399, 388, 389, 390, 391,
D14/338, 339, 356, 347, 379, 380, 384,

Primary Examiner — Marie D. Fast Horse(74) *Attorney, Agent, or Firm* — Wolf, Greenfield &
Sacks, P.C.(57) **CLAIM**The ornamental design for a key pad, as shown and
described.

DESCRIPTION

FIG. 1 is an upper, front, right perspective view of a key pad;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.
The broken lines depict portions of the key pad that form no
part of the claimed design.**1 Claim, 5 Drawing Sheets**US D902,206 S
